For therapeutic purposes

UNITED STATES PATENT OFFICE

2,522,269

ELECTRICAL THERAPEUTIC DEVICE

Fred J. Hart, Salinas, Calif.

Application June 30, 1948, Serial No. 36,221

1 Claim. (Cl. 128—423)

1

My invention relates to improvements in electrical apparatus for producing interrupted alternating magnetic fields for therapeutic uses.

One object is the provision of an electromagnet which, with an alternating current, is adapted to set up electrical currents in human tissues for helping to relieve inflammatory conditions.

Another object is the provision of an electromagnet made up of a core of magnetic material and a coil winding on said core with means for automatically making and breaking an electrical current in a recess in said core so that the current will be made and broken in the magnetic field of said electromagnet.

Another object is the provision of simple and efficient means for accomplishing this end.

Other objects will be apparent from the following description and accompanying drawing, in which:

Figure 1 is a view showing an electromagnet in section and an electrical circuit with the latter mostly in diagram, and

Figure 2 is a diagrammatical view of the electrical circuit.

Referring more particularly to the drawing, the electromagnet of my device preferably has a magnet core made up of a large rear portion 5 and a cylindrical hub portion 6. The magnet may be of any other desired shapes. A coil of wire 7 is wound on the hub portion 6 and formed to fit the front surface of the enlarged portion 5 of the core. The ends 8 and 9 of the coil 7 are led to the middle posts 10 and 11 of a double pole double throw switch. When the blades 12 and 13 are connected with the poles 14 and 15 current supply wires 16 and 17 furnish uninterrupted current to coil 7. An "off and on" switch 18 controls the supply of alternating current electricity to the device.

A thermal switch is mounted on a nonconductor block 19 in a recess 20 in the front end of the core part 6. The arrangement is such that when the current is chopped with the thermal switch mounted on the underside of the block 19 the spark will occur in an electromagnetic field.

The thermal switch consists of a bimetal bar 21 adapted to be bent by heat to open switch points 22 and 23. A resistance coil 24 is wound on said bar 21 with one end secured to the bar 21. The 50

latter bar has one end secured by rivet 25 to block 19. The bar 21 is arranged to hold points 22 and 23 together normally. Current in the coil 24 heats the bar 21 and moves point 22 away from point 23. When said points separate, the current breaks and coil 24 and bar 21 cool again to repeat the cycle.

Switch point 23 is secured by a rivet 26 to block 19 and connected by wire 27 to switch post 14. The other end of coil 24 is secured to block 19 by rivet 28 and connected through wire 29 to switch post 30.

Rivet 25 is connected by a wire 31 to one end of the primary coil 32 of an air core transformer. The other end of coil 32 is connected by a wire 33 to switch point 34.

A condenser 35 is connected between ends of the primary coil 32 and secondary coil 36. The other end of the secondary coil 36 is connected by wire 37 to a treatment plate 38. The latter is mounted on the front face of a front cover 39 which may be of Bakelite or other non-magnetic material.

Front cover 39 is secured at its periphery to the front edge of the rear brass or other metal casing 40 by rivets 41 or their equivalents. The magnet part 5 is secured to the rear casing by brackets, one of which is shown at 42. The casing may be provided with openings 43 for the circulation of air. Suitable insulation material 44 is placed between the coil 7 and the core parts 5 and 6.

In operation, when switch blades 12 and 13 are thrown over to contact with posts 14 and 15, the coil acts continuously and must be operated on alternating current.

When the switch blades 12 and 13 are thrown over to engage posts 30 and 34, current travels from wire 16 to wire 27 and through points 22 and 23 as long as they are closed. While the switch points are closed the heavy part of the current travels over bimetal bar 21 and wire 31 to primary coil 32, then to post 34, blade 12 and over wire 8 to coil 7. The current returns over wire 9 to supply wire 17.

A small part of the current branches off through heater coil 24 to heat and bend the bimetal bar 21 to open the points. While the points are closed, current returns from coil 24 over wire 29 to switch post 30, then blade 13 to supply wire 17.

An important feature is the electromagnet with one large end and one small one to provide a more concentrated flux at the small end. Then, cutting the supply current in the small end and in the concentrated field.

I claim:

In an electrical therapeutic device, the combination of an electromagnet having a coil and a core, said core having a cylindrical portion disposed in said coil and an enlarged portion against one end of said coil, said cylindrical core portion having a central recess in its outer end adapted to provide a relatively weak magnetic field over the recess and a strong magnetic field at the periphery of said end, and an automatically oper- 15

ated switch in said recess and operatively connected to said coil.

FRED J. HART.
